(57) **CLAIM**

The ornamental design for shorts, as shown and described.

DESCRIPTION

FIG. 1 is a front view of shorts, showing a first embodiment of a new design;

FIG. 2 is a rear view of the shorts shown in FIG. 1; FIG. 3 is a right side view of the shorts shown in FIG. 1; FIG. 4 is a front view of shorts showing a second embodiment of the design;

FIG. 5 is a rear view of the shorts shown in FIG. 4; FIG. 6 is a right side view of the shorts shown in FIG. 4; FIG. 7 is a front view of shorts showing a third embodiment of the design;

FIG. 8 is a rear view of the shorts shown in FIG. 7; FIG. 9 is a right side view of the shorts shown in FIG. 7; FIG. 10 is a front view of shorts showing a fourth embodiment of the design;

FIG. 11 is a rear view of the shorts shown in FIG. 10; FIG. 12 is a right side view of the shorts shown in FIG. 10; FIG. 13 is a front view of shorts showing a fifth embodiment of the design;

FIG. 14 is a rear view of the shorts shown in FIG. 13; FIG. 15 is a right side view of the shorts shown in FIG. 13; FIG. 16 is a front view of shorts showing a sixth embodiment of the design;

FIG. 17 is a rear view of the shorts shown in FIG. 16; FIG. 18 is a right side view of the shorts shown in FIG. 16; FIG. 19 is a front view of shorts showing a seventh embodiment of the design;

FIG. 20 is a rear view of the shorts shown in FIG. 19; FIG. 21 is a right side view of the shorts shown in FIG. 19; FIG. 22 is a front view of shorts showing an eighth embodiment of the design;

FIG. 23 is a rear view of the shorts shown in FIG. 22; FIG. 24 is a right side view of the shorts shown in FIG. 22; FIG. 25 is a front view of shorts showing a ninth embodiment of the design;

FIG. 26 is a rear view of the shorts shown in FIG. 25; FIG. 27 is a right side view of the shorts shown in FIG. 25; FIG. 28 is a front view of shorts showing a tenth embodiment of the design;

FIG. 29 is a rear view of the shorts shown in FIG. 28; FIG. 30 is a right side view of the shorts shown in FIG. 28; FIG. 31 is a front view of shorts, showing an eleventh embodiment of a new design;

FIG. 32 is a rear view of the shorts shown in FIG. 31; FIG. 33 is a right side view of the shorts shown in FIG. 31; FIG. 34 is a front view of shorts showing a twelfth embodiment of the design;

(Continued)

FIG. 35 is a rear view of the shorts shown in FIG. 34; and, FIG. 36 is a right side view of the shorts shown in FIG. 34. The figures illustrate the shorts in a state in which the shorts are worn by a wearer.

The left side of the shorts is a mirror image of the right side of the shorts.

The broken lines represent the portions of the shorts that form no part of the claimed design. The cross-hatching indicates contrast in material and/or color with portions of the shorts that are not cross-hatched, and no particular color is claimed. The solid black shading indicates color contrast with non-shaded portions of the shorts, and no particular color is claimed.
